UNITED STATES PATENT OFFICE.

HEINRICH ATHANASIUS BOLZE, OF HANOVER, ASSIGNOR TO CARL GRONERT, OF BERLIN, GERMANY.

DOUBLE-ACTING INJECTOR.

SPECIFICATION forming part of Letters Patent No. 469,674, dated March 1, 1892.

Application filed May 12, 1891. Serial No. 392,496. (Model.)

To all whom it may concern:

Be it known that I, HEINRICH ATHANASIUS BOLZE, a subject of the Emperor of Germany, residing in Hanover, Prussia, have invented 5 a certain new and useful Improvement in Double-Acting Injectors, of which the following is a specification.

The operating of the inlet-valves is effected in the required succession by the turning of 10 a spindle having its bearings in the casing between the injectors. These parts are so combined and proportioned that by the turning of the spindle the inlet-valves are opened by the aid of suitable means interposed be- 15 tween the cock-spindle and the valve-spindles. First one valve is opened and afterward also the other valve.

The accompanying drawings form a part of 20 this specification and represent what I consider the best means of carrying out the invention.

Figure 1 shows a section through the center 25 of the injector. Fig. 2 shows a section on line $x-x$ in Fig. 1, and Fig. 3 on line $y-y$. Figs. 4, 5, and 6 show the positions of the plug of the starting-cock relatively to the positions of the valves.

Similar letters of reference indicate corresponding parts in all the figures where they 30 appear.

The starting-cock a is provided with a spindle b , on which is fixed a disk b' , having a cam or projection b^2 , which operates a cross-head c by acting in a correspondingly-rising groove 35 of the same. The cross-head c is operated by its left arm c' in a hollow of the valve-spindle d and by the right arm c^2 in a hollow of the valve-spindle e' . There is some play allowed in the latter, as shown in Figs. 1 and 4. In 40 these figures the valves of the injector are closed. By turning the spindle or shaft b from the position of Fig. 4 into the position of Fig. 5 the action of disk b' on the cross-head c raises the latter so much as will open 45 the valve d , and the injector A is put into operation for sucking the liquid and forwarding

it through the cock-canals $a' a^3$ into the open air. By further turning the cock out of its position in Fig. 5 into the position in Fig. 6 the cross-head c is further lifted, and thereby 50 the valves $d e$ are wholly opened and the cock-canals $a' a^2 a^3$ closed. By the same movement the cock-canals a' , and thereby the apparatus A, is closed; but at the same time the cock-canals a^2 and valve e are opened, 55 thereby bringing also the injector B to a sucking action. Meantime the injector A will conduct the liquid under a certain pressure through the openings f in the direction of arrow I to the injector B, whereupon the liquid 60 from the injector B, under a corresponding increase of pressure, is conducted through the openings g in the direction of arrow II to the boiler-tube h , provided with a self-acting return-valve h' .

65 I claim as my invention—

1. In a double injector, the spindle having the escape cock or gate a and disk b' , provided with cam b^2 , in combination with the cross-head c , mounted upon said spindle and 70 having a recess engaging the cam b^2 , and the valves having recesses of unequal height engaging the arms of the cross-head, whereby said valves shall be actuated at different periods of the rotation of the spindle, substantially as set forth.

2. The combination of the casing having the passages A B, spindle l , having the gate-cock a and cam-disk b' , the cross-head c , and the valves, the stems of which are provided 80 with recesses engaging the ends of said cross-head, said recesses being of unequal height, substantially as and for the purpose set forth.

In testimony that I claim the invention above set forth I affix my signature in presence of two witnesses.

HEINRICH ATHANASIUS BOLZE.
